DESIGN FOR A CHILD'S CUP

William L. McKay, Evanston, Ill., assignor to Kayware Corporation, Chicago, Ill., a corporation of Illinois

Application January 7, 1948, Serial No. 143,571

Term of patent 14 years

(Cl. D44—9)

To all whom it may concern:

Be it known that I, William L. McKay, a citizen of the United States, residing at Evanston, in the county of Cook and State of Illinois, have invented a new, original, and ornamental Design for a Child's Cup, of which the following is a specification, reference being made to the accompanying drawing, forming a part thereof.

In the drawing:

Fig. 1 is a perspective view of a child's cup, showing my new design;

Fig. 2 is a front elevational view, taken partially in vertical section;

Fig. 3 is a side elevational view; and

Fig. 4 is a top plan view thereof.

I claim:

The ornamental design for a child's cup, substantially as shown.

WILLIAM L. MCKAY.
